UNITED STATES PATENT OFFICE.

CHARLES L. BAUER, OF SPRINGFIELD, OHIO, ASSIGNOR TO THE WARDER, BUSHNELL & GLESSNER CO., OF SPRINGFIELD, OHIO, A CORPORATION OF OHIO.

PAINTING APPARATUS.

SPECIFICATION forming part of Letters Patent No. 703,370, dated July 1, 1902.

Application filed March 16, 1901. Serial No. 51,477. (No model.)

To all whom it may concern:

Be it known that I, CHARLES L. BAUER, a citizen of the United States, residing at Springfield, in the county of Clark and State of Ohio, 5 have invented certain new and useful Improvements in Painting Apparatus, of which the following is a specification, reference being had therein to the accompanying drawings.

This invention relates to improvements in painting apparatus, and more particularly to that class of apparatus in which the article to be treated is coated by a dipping process, which consists, essentially, in submerging the article in a tank or vat containing the paint. Apparatus of this character is now in use comprising an overhead track or way, independent trolley-carriers traveling thereon, from which the articles to be painted are suspended, an elevator comprising, preferably, a vertically-movable section of the track or way, and a counterpoise adapted to counter-balance the weight of the article, so that it may be readily depressed, so as to cause it to be submerged in the liquid paint in the tank. In practice it has been found that as the article is gradually submerged in the liquid its effective weight, acting in opposition to the counterpoise, is correspondingly diminished, so that an increased amount of power is required to further depress the article and cause its complete submergence. Moreover, where the counterpoise is in the nature of a spring the resistance thereof to the depression of the article is a constantly-increasing one and is at its maximum at the time when the greatest force is required to complete the submerging. To overcome these difficulties and provide an apparatus whereby a single attendant may readily and completely submerge an article of any size within the capacity of the apparatus without requiring an increase of effort at the end of the operation or the help of other workmen is the object of my present invention; and to those ends the invention consists in certain novel features, which I will now proceed to describe and will then particularly point out in the claims.

In the accompanying drawings, Figure 1 is 50 an elevation, partly in vertical section, of an apparatus embodying my invention in one

form. Fig. 2 is a vertical sectional view of the same, taken on the line *x x* of Fig. 1 and looking in the direction of the arrow. Fig. 3 is an edge view of the compensating device 55 in its preferred form. Fig. 4 is a side elevation of the same, and Fig. 5 is a view illustrating a modification.

The apparatus in its preferred form comprises an elevated way or track 1, suspended 60 by hangers 2 from the ceiling 3 or otherwise suitably supported. Carriers or trolleys 4 are adapted to travel on this track and support the articles to be treated, one of which is indicated in dotted lines at 5.

6 indicates the dipping-tank, containing the paint or other material with which it is desired to coat the articles, said tank being located at a suitable point underneath the track or way and being provided with a dripping-table 7 adjacent thereto, over which the articles pass after having been dipped.

In connection with the overhead way and carriers and the dipping-tank I employ an elevator 8 of any suitable construction, the 75 same preferably comprising a movable section 9 of the track, adapted to receive and raise and lower the carriers and provided with a yoke 10, by means of which the counterpoise may be connected therewith.

In connection with the elevator a counterpoise is employed, which is preferably adjustable and which may consist of a suitably-coiled spring 11, as shown in Fig. 1, or a weight 12, as shown in Fig. 5. Referring first to the 85 particular construction shown in Figs. 1 and 2, one end of the spring 11 is connected to an adjusting or tension device 13, while the other end has a flexible connection 14, which passes around guide wheels or pulleys 15, its end 90 being secured to a compensating device 16. This compensating device in its preferred form comprises a cam-wheel 17 and a circular wheel 18, mounted so as to move in unison on a common shaft 19. The cam-wheel 17 95 has a peripheral portion 20, which is spiral or of a gradually-decreasing radius from its initial point (indicated at 21) for about three-quarters of its circumference to a point indicated at 22, which is the point of minimum radius, the remainder of the periphery between the points 22 and 21 being substan-

tially straight or flat, as indicated at 23. The flexible connection or rope 14 is secured to the cam-wheel 17 at 24 adjacent to the point of maximum radius, and said flexible connection passes thence to the point of maximum radius and to the counterpoise, the periphery of the cam-wheel being grooved, as indicated at 25, to receive the said rope and hold it in position on the wheel. The circular wheel 18 has a similarly-grooved periphery, as indicated at 26, and there is secured to said wheel at a point in line with the attachment of the rope 14 a second rope or flexible connection 27, which lies within the grooved periphery of the wheel and extends thence downward to the yoke 10 of the elevator. It will be observed that when the elevator is in its raised or normal position the counterpoise has the advantage of a maximum leverage through its flexible connection with the compensating device. As the attendant depresses by hand the article to be treated, thereby lowering it and the elevator, the leverage of the counterpoising-spring upon the compensating device decreases proportionately, so as to neutralize the increased resistance of the spring as it stretches. The leverage decreases to a minimum and remains such during the submergence of the article, at which time the spring is exerting its pull with the leverage represented by the minimum radius of the cam-wheel and the flat portion adjacent thereto. By reason of this fact the attendant does not meet with a constantly-increasing resistance to his efforts to submerge the article, and practically the same amount of force is required throughout the entire vertical range of movement of the article from the start of the downward motion to its complete submergence and subsequently to its return to its normal or elevated position.

It will be understood, of course, that in apparatus of this character the suspended articles are successively carried along the track to the elevator, then lowered or dipped into the paint-tank, and then again raised and forwarded along the continuation of the track, the drip-table receiving the excess of paint after the article leaves the tank.

It is obvious that instead of a spring a counterweight may be employed as a counterpoise to the elevator and article, as shown in Fig. 5. Where this construction is employed, the counterpoise does not offer a constantly-increasing resistance to the depression of the article, and the spiral portion of the cam-wheel may be dispensed with or modified accordingly. One essential feature of my invention, however, whether the spiral be present in the form shown or a modified form or whether it be absent, as in the construction shown in Fig. 5, is the cutting away or flattening of a portion of the cam-wheel 17, where-by when the article being dipped is immersed in the liquid the upward strain exerted by the counterpoise will be correspondingly reduced,

so as to obviate the necessity of extra exertion to hold the article in the paint or other coloring liquid in the tank. For it will be understood that this cut-away or flattened portion is so located that when the article is submerged the pull of the counterpoise is exerted across the cut-away portion and with a reduced leverage, as will be readily understood. It will be understood, of course, that in either case the counterpoise may be adjusted to the weight of the article and elevator, and in the case of the construction employing a spring I have shown an adjusting mechanism which consists of a windlass, to which one end of the spring is connected by a suitable flexible connection. In the case where a weight is employed the same may be added to or diminished in order to adjust the counterpoise to the article.

The form of the compensating device may obviously be varied without departing from the principle of my invention—as, for instance, by the employment of forms other than wheels for the attachment of the flexible connection. I therefore do not wish to be understood as limiting myself to the precise details of construction hereinbefore set forth and shown in the drawings.

Having thus fully described my invention, what I claim as new, and desire to secure by Letters Patent, is—

1. In a painting apparatus, the combination, with a dipping-tank, of an elevator above the same to support the article to be treated, a counterpoise, and a compensating device interposed between the counterpoise and elevator for regulating the action of the counterpoise relatively to the elevator and the article supported thereby, substantially as described.

2. In a painting apparatus, the combination, with a dipping-tank, an overhead track or way, and carriers traveling thereon and adapted to have the articles to be painted suspended therefrom, of an elevator comprising a separable section of the track or way, adapted to receive a carrier when in alignment with the remainder of the track and support said carrier during the vertical travel of the elevator, a counterpoise, and a compensating device interposed between said counterpoise and elevator and adapted to regulate the resistance of said counterpoise to the depression of the elevator, substantially as described.

3. In a painting apparatus, the combination, with a dipping-tank, of an elevator located above the same and adapted to receive and support the articles to be treated, a counterpoise, and a compensating device comprising two members, one flexibly connected with the elevator and the other flexibly connected with the counterpoise, and adapted to regulate the resistance of the counterpoise to the movement of the elevator, substantially as described.

4. In a painting apparatus, the combina-

tion, with a dipping-tank and an elevator located above the same and adapted to receive and support the articles to be treated, of a counterpoise, and a compensating device comprising two members moving in unison, one of said members being circular in form, a flexible connection between said circular member and the elevator, and the other member having a cam-periphery and a flexible connection between the same and the counterpoise, substantially as described.

5. In a painting apparatus, the combination, with a dipping-tank and an elevator located above the same and adapted to receive and support the articles to be treated, of a counterpoise comprising a spring of increas-

ing resistance, and a compensating device consisting of two members moving in unison, one of said members being a wheel or drum circular in form and having a flexible connection with the elevator, and the other of said members having a spiral periphery of decreasing radius and an interposed straight or flat portion and flexibly connected with the counterpoise-spring, substantially as de- 20
25

In testimony whereof I affix my signature in presence of two witnesses.
